(57) CLAIM

The ornamental design for an in line slide switch for disconnecting both conductors, as shown and described.

DESCRIPTION

FIG. 1 is a perspective view of a 1st embodiment of an in line slide switch for disconnecting both conductors showing my new design.

FIG. 2 is a right side elevational view thereof taken in the direction of arrow 2 in FIG. 15;

FIG. 3 is a top view thereof taken in the direction of arrow 3 in FIG. 15;

FIG. 4 is a left side elevational view thereof taken in the direction of arrow 4 in FIG. 15;

FIG. 5 is a bottom view thereof taken in the direction of arrow 5 in FIG. 15;

FIG. 6 is a rear elevational view thereof taken in the direction of arrow 6 in FIG. 15;

FIG. 7 is a front elevational view thereof taken in the direction of arrow 7 in FIG. 15;

FIG. 8 is a perspective view of a 2nd embodiment of an in line slide switch for disconnecting both conductors showing my new design.

FIG. 9 is a right side elevational view thereof taken in the direction of arrow 9 in FIG. 16;

FIG. 10 is a top view thereof taken in the direction of arrow 10 in FIG. 16;

FIG. 11 is a left side elevational view thereof taken in the direction of arrow 11 in FIG. 16;

FIG. 12 is a bottom view thereof taken in the direction of arrow 12 in FIG. 16;

FIG. 13 is a rear elevational view thereof taken in the direction of arrow 13 in FIG. 16;

FIG. 14 is a front elevational view thereof taken in the direction of arrow 14 in FIG. 16 and;

FIG. 15 is a view identical to FIG. 1 with directional arrows included, in accordance with good engineering practices, so as to best indicate in what directions previous views are taken so that nothing regarding the design sought to be patented is ambiguous or left to conjecture; and,

FIG. 16 is a view identical to FIG. 8 with directional arrows included, in accordance with good engineering practices, so as to best indicate in what directions previous views are taken so that nothing regarding the design sought to be patented is ambiguous or left to conjecture.

It is to be understood that any portion of any figure shown in broken lines are for environmental purposes only and form no part of the claimed design.
